UNITED STATES PATENT OFFICE.

THOMAS A. McCALL, OF XENIA, OHIO.

APPARATUS FOR AUTOMATICALLY OPERATING TYPE-WRITERS.

No. 882,263.

Specification of Letters Patent.

Patented March 17, 1908.

Application filed May 29, 1905, Serial No. 262,893. Renewed January 20, 1908. Serial No. 411,756.

To all whom it may concern:

Be it known that I, THOMAS A. McCALL, a citizen of the United States, residing at Xenia, in the county of Greene and State of Ohio, have invented certain new and useful Improvements in Apparatus for Automatically Operating Type-Writers; and I do hereby declare the following to be a full, clear, and exact description of the invention, such as will enable others skilled in the art to which it appertains to make and use the same, reference being had to the accompanying drawings, and to the letters and figures of reference marked thereon which form a part of this specification.

This invention relates to new and useful improvements in automatically operated typewriters, and the object of the invention is to produce a simple and efficient means, whereby a strip may be perforated to form a stencil roll to be used for allowing balls to be fed at predetermined moments to positions where they coöperate with mechanism for causing the type levers of the machine to be operated.

The invention consists further in the provision of an automatic typewriter or duplicator, in which, after the original copy has been made, any number of copies may be automatically made from the original.

The invention comprises various details of construction and in combinations and arrangements of parts which will be hereinafter fully described and then specifically defined in the appended claims.

I illustrate my invention in the accompanying drawings, in which:—

Figure 1 is a side elevation of my invention. Fig. 2 is a top plan view. Fig. 3 is a view, showing parts of the invention in transverse section and illustrating a top plan view of a part of the machine. Fig. 4 is an enlarged detail in side elevation of a part of my machine. Fig. 5 is a sectional view longitudinally through the machine. Fig. 6 is a cross-sectional view, showing parts of the invention in elevation. Fig. 7 is a detail sectional view on line $x-x$ of Fig. 9, showing the manner of feeding balls to coöperate in forming a stencil strip, and also for causing the imprint of a letter or character. Fig. 8 is a detail sectional view on line $x-x$ of Fig. 9^a, showing the manner in which a ball is fed by a

perforated strip to a chute. Fig. 8^a is a detail sectional view on line $y-y$ of Fig. 9^a. Fig. 9 is a sectional view, showing in dotted outline the various chutes through which the balls pass, and also illustrating an elevation of the clutch mechanism. Fig. 9^a is a top plan view of Fig. 8. Fig. 9^b is a detail perspective of a perforated shaft. Fig. 10 is a detail view, showing in edge elevation levers which actuate clutch mechanism, said view showing ball-actuated levers in sections which are depressed. Fig. 11 is a sectional view through the clutch mechanism, and showing in side elevation a portion of a corrugated cylinder which coöperates with balls and levers to actuate clutch throwing mechanism. Fig. 12 is a sectional view of one of the removable reels. Fig. 13 is a detail view showing the manner of mounting one end of a reel, and Fig. 14 is a detail perspective view of a ball feeding plunger.

Reference now being had to the details of the drawings by letter, A designates the frame of the apparatus, having a series of key levers B mounted upon a pivotal rod B', shown in Figs. 1 and 2 of the drawings, said key levers each representing a certain numeral, word or other character, and each is provided with a finger B², which is pivotally connected at B³ to a plunger B⁴, each of said plungers being acted upon by a spring B⁵, the office of which is to normally hold the plunger at its farthest outward throw and to return a key lever B to its normal position after having been depressed. Each of said plungers B⁴ is mounted horizontally in a groove or aperture in the opposite walls of the hopper C in which the balls C' are placed. Each of said plungers has a perforation C², therein to receive a ball, as shown clearly in Fig. 5 of the drawings. Journaled in an enlarged cylindrical outlined recess at the bottom of the hopper is a shaft D, which has a diametrically disposed hole D' formed therein, and said shaft is provided for the purpose of preventing the balls from being fed from the hopper during a certain operation of a mechanism, when the balls are not performing any function, and as will be presently described.

D² designates a chute, which communicates with the passageway D³, through which the balls are fed from the hopper, and the lower

- end of the passageway D^2 communicates with a passageway D^4 down which balls are allowed to fall from a second hopper E, shown in Figs. 1 and 5 of the drawings.
- 5 The two passageways D^2 and D^4 merge together at their lower ends, and positioned adjacent to the juncture of said passageways is a drum F, having a series of metallic strips F' seated longitudinally in recesses in its circumference and spaced apart, forming a series of projections adapted to catch the balls as they are fed through the chute into the positions shown in Fig. 5 of the drawings.
- 10 While I have shown in the drawings a drum made up of strips, as described, it will be understood that said drum may all be cast in one piece, if desired, and provided with corrugations, which would answer the purpose of the strips shown and described.
- 15 20 Leading from the lower ends of the two passageways D^2 and D^4 is a chute D^5 , which is shown in section in Fig. 5, and in Fig. 6 the upper margin of said chute is designated in dotted lines, and down which the balls, after 25 having performed their function, roll into the lower end of the casing D^6 , a portion of which is broken away in Fig. 6 of the drawings, and in which the balls are raised by means of a spiral elevating worm D^7 . Mounted within 30 said casing is a strip D^8 , which is grooved slightly, in order to form means to guide the ball in a straight line vertically, as it is raised by the worm to the upper portion of said casing, from which it makes exit through the 35 pipe D^9 , into the branching pipes D^{10} , back to the hoppers C and E.
- Power is applied to the machine by means of a motor G, shown in Fig. 1 of the drawings, said motor being provided with a shaft 40 G', and having a worm G² thereon, which is in mesh with a gear wheel G³ fixed to a shaft G⁴, which is journaled in the frame of the apparatus, and which shaft also carries the drum F, before referred to.
- 45 G⁵ and G⁶ are gear wheels of different diameters, which are fastened by means of screws G⁷, shown in Fig. 3 of the drawings, to the worm wheel G⁸, and G⁸ is a gear wheel which is mounted upon a stub shaft G⁹ fixed 50 to the frame of the apparatus, and said gear wheel G⁸ is in mesh with the teeth of the gear wheel G⁵, and rotates continuously while the operating shaft G⁴ is in motion.
- 55 G¹⁰ designates a gear wheel, which is designed to have an intermittent movement, and is actuated by means of a split friction ring G¹¹, which is shown in section in Figs. 3 and 4 of the drawings. Said split ring G¹¹ is mounted intermediate an annular flange 60 G¹², upon the gear wheel G⁸, and an annular flange G¹³, formed upon the outer face of the wheel G¹⁰.
- 65 G¹⁴ designates a pin, which is seated in a recess of the wheel G⁸, and has a finger g, shown in Fig. 4 of the drawings, which is fas-

tened at right angles to said pin, and is positioned in the space intermediate the ends of said split ring.

H designates a gear wheel, which is mounted upon a shaft H', said wheel H being held upon the shaft by means of a threaded screw h, shown in Fig. 3 of the drawings, which is fitted in the hollow threaded end of the shaft H'.

H² designates a lever, which is pivotally mounted upon a pin H³, projecting from the face of the wheel H at one side of its center, and the other end of said lever is pivotally connected to a pin H⁴ carried by the crank arm H⁵, which crank arm is fixed to a shaft H⁶ with which reel I rotates. A ratchet wheel H⁸ is also fixed to said shaft H⁶, and a spring-pressed pawl H⁹ is mounted upon the pivot H⁴, and its free end is held in engagement with the teeth of the ratchet wheel by means of a spring H¹⁰. By the provision of said ratchet wheel and the connections described, it will be noted that at each rotary movement of the gear wheel H an intermittent motion will be imparted to the wheel H⁸, for the purpose of feeding a stencil strip, which will be hereinafter described, forward a certain distance.

I designates a reel or winding drum upon the shaft H⁶, and upon which the stencil strip I' winds after passing through the slot I² below the chute D⁵, said strip passing underneath a roller I³, and thence about a reel I⁴.

J designates a series of levers, which are pivotally mounted upon shaft J', which is held in the opposite walls of the machine, and J² and J³ designate springs, each being connected at its lower end to a lever J, and its upper end to a perforated ear g' upon the chute D, the office of said springs being to normally hold said levers at their highest throw, as shown in Figs. 1, 4 and 5 of the drawings. The forward free end of each lever J is preferably convexed, as shown at J³, and projects into the chute, into which the balls are adapted to fall, and is designed to hold the ball from falling to the bottom of the chute until one of the corrugations or strips F', seated in the circumference of said drum F, forces the ball against the lever, causing the same to tilt out of the path of the ball, after which the ball will be allowed to fall to the bottom of the inclined chute D⁵, and a spring J² will return the lever J to its normal position after the ball has passed the end of the lever.

K, K designate punches or plungers, each being pivotally connected at K' to a lever J, and each punch K has a vertical play in a guide aperture K², shown clearly in Fig. 5 of the drawings, said punches being depressed with the levers to cause perforations to be formed in the strip I'. The inner ends of the levers J are pivotally connected to rods J⁴, each of which is adapted to be connected to

the ordinary type lever of a typewriter, whereby, when the apparatus is adjusted for printing a letter, by the utilization of the prepared stencil strip, in the manner to be 5 presently described, impressions may be made upon a sheet of paper upon the roll of a typewriter, but which typewriter and type-carrying levers are not illustrated in the drawings, as they form no part of the present 10 invention.

Referring to Figs. 4 and 5 of the drawings, will be seen a shaft L, which is shown in section in Fig. 5, and in end elevation in Fig. 4, which shaft is mounted in elongated slots L' 15 formed in the frame of the machine, and said rod or shaft is positioned normally in contact with the under edges of the series of levers J, and is depressed the limit of the slot L', as each of the several levers J is tilted.

Referring to Fig. 4 of the drawings, will be seen a stop lever L², one end of which is adapted to be positioned in the path of the finger g to cause said finger to bear against the split ring at each rotary movement of the 20 wheel carrying said finger, for the purpose of holding the ring out of engagement frictionally with the adjacent face of the annular flange G¹², whereby the wheel G¹⁰ may be at rest momentarily during the punching of a 25 perforation in the strip I'. A spring L³ is secured at one end to the stop lever L², and at its other end is fastened to a pin L⁴ upon the wall of the frame of the machine, and the office of said spring is to normally hold the 30 rod or shaft L in the position shown in solid lines in Fig. 4, and in cross section in Fig. 5, and the stop lever in the position shown in solid lines in Figs. 4 and 5, in which the inner free end thereof is in the path of the rotatable 35 finger g.

When it is necessary to prevent the shaft or rod L from being actuated by the depression of a lever J, I have provided a button L⁵, pivotally mounted upon the shaft L⁶, said 40 button having a knob L⁷, and L⁸ designates a lug designed to limit the outer throw of said button, and assuming the position shown in solid lines in Fig. 4 of the drawings. The dotted position of the button L⁵ illustrates 45 the stop lever as being tilted down out of the path of the finger g, and also holding the rod or shaft L in the position shown in dotted lines in Fig. 4 of the drawings, and in which position said shaft or rod will be free from the 50 levers J, if any of the same are tilted. When the stop lever is held in the position shown in dotted lines, and in order to hold the clutch mechanism from operating the gear wheel G¹⁰, I provide a stop button M, one end of 55 which is pivoted to the frame of the machine, and its other end adapted to bear against the finger g causes the friction of the split ring to disengage the flange G¹¹ of the gear wheel G⁸. This adjustment of the machine is effected during the printing from 60

a stencil roll, and when the intermittent movements are not required, as in the formation of the stencil strip.

Referring to Fig. 5 of the drawings will be seen in dotted outline a lever L², which is adapted to support the far end of the rod or shaft J' and serves to hold the same by a suitable spring, not shown, in the position shown in said figure.

N designates a reel upon which the stencil strip is adapted to wind from the reel I⁴, when the stencil strip is being utilized for the purpose of reproducing a letter upon a typewriter, and said stencil strip passes over the roller N' and between the rollers N² and N³. Referring to Fig. 5 of the drawings, it will be seen that said stencil strip passes horizontally through the chute through which the balls are fed and adjacent to the shaft D through which the balls are allowed to fall on to the stencil strip and be carried by the latter as a ball falls partially through a perforation, in the manner shown in Fig. 8^a of the drawings. The reel I⁴, a detail view of which is shown in Fig. 12 of the drawings, is made detachable, and is held to a stub shaft N⁴, a detail perspective of one end of said shaft being shown in Fig. 13 of the drawings, and which has splined thereto a clutch jaw N⁶, and N⁵ designates a gear wheel which is journaled upon a bearing N⁷ by means of a collar N⁸, which is held by means of a set screw to the shaft. The shaft N⁷ of the reel, one end of which is shown in detail in Fig. 13, has a projecting part N⁹, carrying a lug N¹⁰, which projection and lug are designed to enter, respectively the recess N¹¹ and the hole N¹² in the end of the stub shaft N⁴, whereby the reel may rotate with said stub shaft. A hook N¹³ is fastened to the circumference of the reel for attachment to the end N¹⁴ of the stencil roll. The opposite end of the shaft of the reel is engaged by a spindle O, which is held by means of a spring O' normally at its farthest inner throw, and O² designates a knob, which is fastened to the other end of said spindle, whereby the latter may be pulled out to release the reel. Referring to Fig. 4 of the drawings will be seen a rock shaft P, mounted in the bearings P' upon the frame of the machine, and fixed to one end of said shaft is a crank arm P², the end of which is connected to said clutch N⁶ splined upon the shaft N⁷, which clutch N⁶ is designed to mesh with the teeth upon the face of the gear wheel N⁵, shown in Fig. 12 of the drawings. The gear wheel N⁵ is in mesh with a gear P⁴ mounted upon the stub shaft P⁵, and P⁶ designates a gear wheel, which is mounted upon the stub shaft P⁷, and the wheel P⁶ is in mesh with the gear wheel G⁶, which rotates with the main driving shaft G¹.

Keyed to the shaft P is a collar Q, having an integral arm Q', which is pivotally connected to a clutch Q², mounted upon the stub 130

shaft Q^3 , and Q^4 designates a gear wheel mounted loosely upon the shaft Q^3 , and having teeth Q^5 upon one face thereof, which are adapted to intermesh with the teeth of the clutch Q^2 , as shown clearly in Fig. 10 of the drawings. The clutch Q^2 is splined to the stub shaft Q^3 in the usual manner, and fixed to the end of the shaft P is an angled lever Q^6 , one end of which is provided with a series 19 of annular recesses Q^7 , and is adapted to be tilted into three different positions by the levers R , R' and R^2 , respectively, said levers being pivotally mounted upon a shaft R^3 , shown clearly in Fig. 10 of the drawings, and 20 the lower angled end of each of said levers, R , R' and R^2 , carries an anti-frictional roller R^4 , which is positioned underneath one of the tilting levers J . It will be observed that the upper end of the lever R is angled and turned 25 rearwardly, while the upper free ends of the levers R' and R^2 are bent in the opposite directions. The office of the lever R is to cause the angled lever Q^6 to tilt to a horizontal position, or in the intermediate position 30 shown in dotted lines in Fig. 4 of the drawings, and in solid lines in Fig. 10. It will be noted that the arm of the lever Q^6 is tapered to a point, as at Q^7 , and is adapted to rest in a notch in the free end of a flexible arm Q^8 , 35 which is fastened at Q^9 to the frame of the apparatus. The edges of the head of said arm Q^8 are inclined and adapted to engage with the inclined edges of portions of the arm Q^6 , for the purpose of throwing the angled lever Q^6 to its highest or lowest throw in either direction, after the point or tapering 40 end of the arm Q^6 is released from the recess in the end of said arm Q . The lever R' is so constructed and adjusted that at a predetermined moment, as it is rocked, its upper 45 free end coming in contact with the upper edge of the angled lever Q^6 will cause the same to be thrown down to its lowest position, or in the position shown in dotted lines in Fig. 4 of the drawings. The third lever R^2 is adapted to be actuated at a predetermined moment by the depression of one of the several levers J , for the purpose of throwing the angled lever, so that its shank portion 50 will assume a horizontal position, as illustrated by solid lines in Fig. 10, in which position the two clutch mechanisms will be out of gear, while the address printing features of the invention, presently to be described, are 55 in operation, and at which time it is desired to allow other parts of the apparatus to remain at rest. Said levers R , R' and R^2 have connected thereto, respectively, the springs r , r' and r^2 , which are fastened to the frame 60 of the machine, and are provided for the purpose of returning the several levers to their normal positions after being rocked by the tilting of the levers J .

In order to prevent any of the balls being 65 fed to the inclined passageway D^2 , when the

paper is being re-wound upon the reel I or for any other purpose, I provide the crank arm D^{10} fixed to the shaft D , and which arm is actuated by means of the rod D^{11} , fastened to a crank arm D^{12} fixed to the shaft P .

The portion of the apparatus in which the reels for holding the stencil strip S^4 , which actuates the mechanism for printing the addresses of letters, comprises two reels S and S^8 , the former of which is similar in construction to the reel shown in Fig. 12 of the drawings, and is detachably held upon the frame of the apparatus; and the stencil strip from the reel S is adapted to pass underneath the roller S^2 , through the upper end of the chute D^4 , and immediately under the rock shaft S^3 , which is similar in construction to the shaft D , before referred to, and has a milled wheel S^X , shown in Fig. 3 of the drawings, whereby the same may be turned to prevent the passage of balls from the hopper E . Said shaft is perforated to allow balls to pass into the chute D^4 from the hopper E . The stencil strip S^4 passing underneath the roller S^2 winds upon a reel S' ; which has a bevel gear S^7 at one end thereof, which is in mesh with a bevel gear S^8 , shown in Fig. 2 of the drawings, and said bevel gear S^8 is fastened to a shaft S^9 , mounted in suitable bearings projecting from the frame of the machine, and the lower end of the shaft S^9 carries a bevel wheel S^{10} , which is in mesh with a loosely journaled bevel gear S^{11} mounted upon the main operating shaft G^4 . Mounted upon the main driving shaft G^4 , opposite the end carrying the gear wheel G^3 , is a clutch S^{12} , shown in Fig. 11 of the drawings, and the teeth upon said clutch are designed to engage the teeth upon the edge of the hub of the gear wheel S^{11} . Mounted in a bracket arm S^{13} , projecting from the frame of the machine, is a pivotal shaft S^{14} , upon which an angled lever S^{15} is fixed, an arm of said angled lever being pivotally connected to said clutch S^{12} , which is splined upon the shaft G^4 , and the end of the shank portion of said lever is positioned underneath one of the several levers J , whereby as said particular lever is depressed, the angled lever S^{15} will be tilted and the clutch mechanism operated. Said lever S^{15} has an arm S^{20} projecting therefrom, and its end is pointed, as seen clearly in Fig. 11, and is normally held in one position or another by means of the angled end S^{21} at the end of the flexible arm S^{22} .

S^{16} is a lever, having a stop S^{17} at one end thereof, and is mounted upon a pivotal pin S^{18} supported in a lug S^{19} upon the frame of the machine, and one end of said lever S^{16} is positioned underneath one of the levers J , whereby as the lever J is depressed said lever S^{16} will be tilted, so that the stop S^{17} thereon will throw the lever S^{15} upward, and the clutch actuated thereby out of gear, which will stop the feeding of the strip stencil 130

mechanism. A spring S^{23} is fastened to the frame of the apparatus, and bears yieldingly against the lever S^{16} , whereby the same, having been tilted upon its pivot, may be 5 returned to its normal position.

Referring to Figs. 2 and 4 of the drawings, will be seen a hand wheel W , which is fixed to a shaft S^{14} , shown in section in Fig. 11 of the drawings, and is provided for the purpose of actuating the clutch S^{12} by hand, if it is desired to stop the rotary movement of the reel S' .

In operation, the strip in which the perforations are to be formed is wound upon the reel I^4 , and the end of the strip being passed underneath the roller I^3 , through the slot I^2 below the chute D^3 , and fastened to wind about the reel I , as shown in Fig. 5 of the drawings, the motor is started, and a continuous movement is imparted to the driving shaft G^4 through the medium of the shaft G and its gear connection with the wheel G^3 fixed to the shaft G^4 . The operator wishing to print a certain letter, figure or character 15 depresses a key lever B , representing a letter, numeral or other character, and a ball will be driven forward by the plunger pivoted to said key lever, and when the ball comes into registration with the chute D^3 , it will fall 20 into the chute D^2 and assume the position, as shown in Fig. 5 of the drawings, where it comes into contact with the end of a lever J . The corrugation or strip F' upon the cylinder F , which is constantly rotating while the 25 machine is in operation, will contact with the ball and cause the lever J to tilt to allow the ball to pass the free end of said lever. As the lever J tilts, the plunger or punch K will cause a perforation to be made 30 in the strip I' , and after the perforation has been made, the lever J will be returned to its normal position, shown in Fig. 5 of the drawings, by means of the spring J^2 . As 35 the lever J tilts, its under edge will contact with the shaft L and cause the stop lever L^2 to tilt, so that its free end will be free from the finger g which will cause the wheel G^{10} , which is frictionally engaged by the split 40 ring G^{11} , to rotate, and the gear wheel H , being in mesh with the gear wheel G^{10} , will also be rotated.

The lever H , which is pivotally mounted eccentrically to the wheel H , will upon its downward throw cause an intermittent 45 movement to be imparted to the reel I by the dog H^3 engaging a tooth of the ratchet wheel H^8 . After the finger g has passed the end of the stop lever L^2 , the latter and the shaft L , carried thereby, will be returned to 50 their normal positions by means of the spring G^3 , and the free end of said stop lever L^2 will be in the path of the finger g , and releasing the inner marginal edge of the split ring from frictional contact with the flange of the 55 wheel G^8 , the wheel G^{10} will cease its rotary

movement and also the gear wheel H , which is geared thereto. The strip of paper, which is being punched, is now at rest and in readiness to receive another perforation, which is caused by allowing the second ball to fall 70 through the chute D^3 by the depression of another key lever B , representing another letter, numeral or character, and the operation is repeated. Each time the lever J is tilted through the medium of the ball, which is positioned intermediate the free end of the lever and the strip or corrugation upon the drum F , an intermittent movement is imparted to the reel I , for the purpose of feeding the strip I' forward a short space, corresponding to the margin between the lines to be typewritten. This operation is repeated until the stencil strip, representing the matter which it is wished to be printed, is completed. 80

The stencil strip is now completed with the exception of one perforation, and the last perforation to be made in the strip is formed by the actuation of a certain key lever B , which will cause a ball to be actuated intermediate a lever J and the cylinder F , which will cause the tilting lever R to rock upon its pivotal bearing, and as said lever R tilts, the shaft P will rock and the crank arm P^2 at the opposite end of the shaft 90 will cause the clutch N^6 to be thrown into mesh with the teeth on the edge of the pinion N^5 , and cause the reel I^4 to rotate, winding up the stencil strip upon said reel I^4 . The end of the stencil strip being detached 95 from the reel I , after the strip I' has rewound upon the reel I^4 , then the end of the strip, which was formerly fastened to the reel I , is passed over the roller N' , through the slot at the upper end of the chute D^2 between the 100 two rollers N^2 and N^3 , and is fastened to and is adapted to wind upon the reel N .

A second stencil strip adapted for allowing balls to actuate mechanism for printing addresses upon letters is formed by the punching apparatus, before described, and being wound upon the reel S is passed underneath the roller S^2 through a slot at the upper end of the passageway of chute D^4 underneath the roller S^5 , and is secured to and adapted 110 to wind upon the reel S' . The parts of the apparatus being thus arranged, the mechanism is in readiness to print automatically, first the address of a letter, and afterward the body of the letter. During the printing 120 of the addresses and body portion of a letter, the catch lever L^2 is held with its free end tilted down, as shown in dotted lines shown in Fig. 4 of the drawings, by means of the dog L^5 , which is swung into the position 125 shown in dotted lines in said figure, and the stop M is swung up into the path of the finger g to prevent the same from rotating, said stop M taking the place of the lever L^2 , which latter, when positioned as shown in 130

dotted lines, will hold the shaft L from contact with the several levers J, as they are tilted down in the act of causing the type-carrying levers of the typewriting machine 5 to be actuated.

The shaft S¹⁴ may be turned by means of the hand wheel W, shown in Fig. 4, whereby the clutch S¹² may be thrown into engagement with the teeth upon the hub portion of 10 the gear wheel S¹⁰, thereby imparting a movement to the reel S' through the medium of the gear wheel S¹⁰, the shaft S⁹, the bevel gear S⁸ and the gear S⁷ upon the spindle of the reel S'. The shaft S³ being in position, 15 so that the perforations therein will be in registration with the passageway through the hopper into the passageway D⁴, the several balls, each representing a word, letter, numeral or character, will fall from the 20 hopper E and rest upon the surface of the strip S⁴, shown in Fig. 5 of the drawings. As the strip is unwound from the reel S and wound upon the second reel S', and as a perforation in the stencil strip comes under 25neath in one of the apertures in the shaft S³, said ball will fall into the recess, in the manner shown in Fig. 8^a of the drawings, the ball, falling upon the horizontal grooved portion in the wall of the passageway, will be fed 30 forward with the paper until the ball clears said grooved portion, and comes over the passageway D⁴, down which the ball will fall by gravity to a position shown in Fig. 5, and as a strip of corrugation upon the circumference of the cylinder F forces the ball against the end of the lever J, the latter will tilt, and its rear end will actuate a corresponding type-carrying lever upon a typewriter, not shown, and cause an impression 35 to be made. After the ball has passed the end of the lever J, the latter will be returned to its normal position by means of the spring J². As the strip S⁴ presents another perforation, representing a letter, numeral, or 40 other character, another ball will be fed forward in a like manner and deposited in the chute D⁴, and the same operation is repeated, the ball, as it passes the end of the lever J, falling into the chute D⁶ down which it rolls 45 to the lower end of the chute, from which it is elevated and automatically returned to one of the other of the hoppers by means of the vertically disposed elevating worm. After the address has been printed in the 50 manner described, the address mechanism is thrown out of gear simultaneously with the throwing into gear of the apparatus which prints the body portion of a letter, and the means for throwing these two pieces of the 55 apparatus, one out of operation, and the other into operation, is effected by a ball, which falling from the hopper E passes through a perforation in the strip S⁴, and causes the lever S¹⁵, shown in Fig. 11 of the 60 drawings, to be tilted down, and the latter 65

throwing the clutch S¹², which puts the mechanism for actuating the reel S' out of gear. Simultaneously with the throwing of the reel S' out of gear, another ball passes through a perforation in the strip S⁴, and passing 70 through the chute D⁴ will cause the lever R' to tilt upon its pivot, and the upper end of said lever coming in contact with the arm of the angled lever Q⁷ will cause the shaft P to rock, and the crank arm Q' carried by said 75 shaft will throw the clutch Q² into mesh with the teeth of the pinion wheel upon the shaft carrying the reel end. As the shaft rocks to throw into mesh the clutch Q², the angled lever P² at one end of the shaft P will throw 80 the clutch N⁶ out of mesh with the pinion wheel upon the shaft, carrying the reel I⁴, thus causing the strip I' to unwind from the 85 reel I⁴ and wind upon the reel N.

Simultaneously with the rocking of the 90 shaft P, the crank arm D¹², which is fixed thereto, will pull down upon the rod D¹¹, shown clearly in Fig. 4 of the drawings, and cause the shaft D having the perforations 95 therein, to be rocked so that said perforations will be in registration with the vertical passageway of the hopper C containing the balls, as shown in Fig. 5 of the drawings. When the body portion of a letter is being 100 printed, it will be understood that the plunger B⁴ is retracted into the position shown in Fig. 7 of the drawings, in which the aperture in said plunger will be in alignment with the vertical passageway of the hopper C, to allow the balls to pass readily 105 into the hopper through the shaft D and onto the surface of the stencil strip I', in the manner shown in Fig. 8^a of the drawings. As a certain perforation, representing a 110 letter, numeral or character, comes underneath a ball, the latter will fall into the perforation, as shown in Fig. 8^a, and will be fed forward by the advancing paper until the ball falls from the horizontally disposed portion in the wall of the chute D², and 115 falling down the latter will come into contact with the end of a lever, and the rotary movement of the constantly moving cylinder will force the ball by the lever, causing the latter to tilt in the same manner as in printing the address. This operation is 120 repeated until the last letter, numeral or character of the body portion of the letter has been printed, and when it is desired to rewind the stencil strip from the reel I⁴ to 125 the reel I⁴, a certain ball falling through a perforation in the strip I' will cause a lever J to be tilted, which will actuate the angled lever R', the upper angled end of which will cause the lever Q⁷ to tilt to its lowest position, and rocking the shaft P will cause the clutch mechanism Q² to be thrown out of gear, and the clutch N⁶ into mesh with the teeth of the pinion wheel N⁵, thus causing the reel I⁴ to 130 wind up the stencil strip. As the shaft P

rocks, the perforated shaft D will be turned so that it will be impossible for balls to pass through said shaft D during the return of the rewinding of the stencil strip upon the reel I⁴. When the rewinding is nearly finished, a certain perforation will catch a ball, as illustrated in Fig. 8 of the drawings, and cause the same to be fed forward slightly and fall into the chute D², and, in the manner described, actuate a lever J, which tilting against the lever S¹ will throw the clutch S¹² into mesh with the bevel gear S¹¹, and the address printing mechanism will be started by causing the strip S⁴ to unwind from the reel S and to wind upon the reel S', and the same operation will be repeated of printing a new address, after which the printing mechanism for printing the body portion of a letter will be automatically set into operation, and the same may continue indefinitely and automatically printing any number of letters each with a distinct address and with the same body portion. When it is desired to insert a new roll of stencil, the two reels S and I⁴ may be readily replaced by others occupying the same positions.

Thus it will be seen from the mechanism embodying my invention that the limit of speed in writing addresses and letters is limited by the speed of the typewriter, and that all the parts of the apparatus are automatic in their action from start to finish.

While I have shown a particular form of apparatus, illustrating my automatic mechanism for forming stencil strips for actuating levers of a typewriter, it will be understood that I may vary the details in different ways, if desired, without in any way departing from the spirit of the invention.

Having thus fully described my invention, what I claim as new and desire to secure by Letters Patent, is:—

1. An automatic actuating apparatus for typewriting mechanism, comprising a movable stencil strip, balls adapted to pass through perforations of said strip, and mechanism co-operating with said balls to cause a type bar to be actuated, as set forth.

2. An automatic actuating apparatus for typewriting mechanism, comprising a movable stencil strip, balls adapted to be moved by said strip and to pass through the perforations of the latter, and mechanism co-operating with said balls for causing a type bar to be actuated, as set forth.

3. An automatic actuating apparatus for typewriting mechanism, comprising a movable stencil strip, balls adapted to fall into the perforations of said strip, and be moved by the latter, and mechanism co-operating with said balls for actuating a type bar, as set forth.

4. An automatic actuating apparatus for typewriting mechanism, comprising a plu-

rality of stencil strips, balls adapted to pass through the perforations of said strips, means for moving one of said strips while the other is at rest, and mechanism co-operating with said balls for causing a type bar to be actuated, as set forth.

5. An automatic actuating apparatus for typewriting mechanism, comprising a plurality of stencil strips, balls adapted to fall into perforations of said strips and be moved by the latter, means for moving one of said strips while the other is at rest, and mechanism co-operating with the balls for causing a type bar to be actuated, as set forth.

6. An automatic actuating apparatus for typewriting mechanism, comprising a movable stencil strip, balls adapted to pass through the perforations of said strip, when the latter is moving in one direction, mechanism co-operating with said balls for causing a type bar to be actuated, and means for preventing balls from passing through the perforations of said strip when the latter is moved in a reversed direction, as set forth.

7. An automatic actuating apparatus for typewriting mechanism, comprising a hopper, a movable stencil strip, a cylinder with projections upon the circumference thereof, a pivotal lever adapted, as it is tilted, to cause a type bar to be actuated, said strip designed to move a ball falling into a perforation of said strip, and allowing the same to fall intermediate said cylinder and lever, as set forth.

8. An automatic actuating apparatus for typewriting mechanism, comprising a plurality of stencil strips, a hopper positioned over each strip, balls within said hopper, a rotatable cylinder, having projections upon the circumference thereof, tilting levers adapted to actuate type bars, passageways, adapted to direct a ball as it passes through one or the other thereof to a position intermediate the end of one of said levers and said cylinder, as set forth.

9. An automatic actuating apparatus for typewriting mechanism, comprising a hopper, a movable stencil strip passing through and guided in a slot in the lower portion of the hopper, a rotatable cylinder, having projections upon the circumference thereof, a tilting lever, a passageway leading from said hopper to a position adjacent to the tilting end of said lever, and into which passageway a ball is fed by said strip, said lever co-operating with the ball and cylinder to cause a type bar to be actuated, as set forth.

10. An automatic actuating apparatus for typewriting mechanism, comprising a hopper, a movable stencil strip, passing beneath said hopper, a rotatable perforated shaft mounted within said hopper, means for turning said shaft so that the perforations therein will be in registration with the hopper while said strip is moving in one direction, and

- means for turning said shaft to prevent balls from passing from the hopper while the strip is moving in the opposite direction, a tilting lever designed to actuate a type bar, and a 5 rotatable cylinder with projections upon the circumference thereof, designed to coöperate with a ball fed through a perforation of said strip for causing said lever to tilt, as set forth.
- 10 11. An automatic actuating apparatus for typewriting mechanism, comprising a hopper, a stencil strip, reels upon which the same is adapted to wind, a rotatable cylinder, a lever designed, as it is tilted, to actuate 15 a type bar, clutch mechanism in connection with said reels, a second lever, and connections between the latter and said clutch mechanisms, balls adapted to pass through perforations of said strip and coöperating 20 with said cylinder and levers to cause a type bar or clutch mechanism to be actuated, according as the strip moves in one direction or the reverse direction, as set forth.
12. An automatic actuating apparatus for 25 typewriting mechanism, comprising a hopper, a stencil strip, reels upon which said strip is carried passing underneath said hopper, a passageway, having an offset, which extends underneath the exit end of said hopper and over which offset said strip is positioned, a ball adapted to fall into a perforation of said strip and rest upon the bottom of said offset and fed by the strip into said 30 passageway, a rotatable cylinder, and a tilting lever adapted to coöperate with a ball and said cylinder to actuate a type bar as said lever is tilted, as set forth.
13. An automatic actuating apparatus for 35 typewriting mechanism, comprising hoppers, a plurality of movable stencil strips, each passing beneath a hopper, passageways leading from each hopper and communicating at their lower ends, each passageway having an offset adjacent to the exit end of a hopper, and into which offset a ball is adapted to 40 fall through a perforation in one of said strips and be fed by a strip into a passageway, a rotatable cylinder and tilting levers, between the free ends of which and said cylinder balls are directed from said passageways, said levers being tilted by the balls to 45 cause type bars to be actuated, as set forth.
14. An automatic actuating apparatus for 50 typewriting mechanism, comprising a hopper, a movable stencil strip positioned underneath said hopper, and adapted to receive singly balls from the hopper, a passageway, having an offset communicating with the hopper, said strip designed to receive in one of its perforations a ball from the 55 hopper and to move the same into said passageway, a cylinder, strips seated therein and projecting beyond the circumference of the cylinder, tilting levers with their free 60 ends positioned adjacent to the circumference of said cylinder, and said passageway designed to direct a ball intermediate the cylinder and the end of the lever, the latter being adapted, as it is tilted by a ball, to 65 actuate a type bar, as set forth. 70
15. An automatic actuating apparatus for typewriting mechanism, comprising a hopper, reels, stencil strips winding about said reels and passing underneath said hopper, a passageway, having an offset at its upper end 75 communicating with said hopper, a cylinder, having projections upon the circumference thereof, extending into said passageway, levers with their free ends positioned adjacent to the circumference of said cylinder, said levers being tilted by the balls in contact with the ends of the lever and depressed by a projection of said cylinder, and means for returning the ball to the hopper, as set forth. 80
16. An automatic actuating apparatus for 85 typewriting mechanism, comprising a hopper, reels, stencil strips winding about said reels and passing underneath said hopper, a passageway, having an offset at its upper end 90 communicating with said hopper, a cylinder, having projections upon the circumference thereof, extending into said passageway, levers with their free ends positioned adjacent to the circumference of said cylinder, said levers being tilted by the balls in contact 95 with the ends of the lever and depressed by a projection of said cylinder, the lower portion of the passageway having a lateral projection, the bottom of which is inclined and down which the ball is adapted to roll as it 100 passes the cylinder, an elevating worm for raising a ball, and passageways leading from the upper portion of the worm to said hopper, as set forth. 105
17. An automatic actuating apparatus for 110 typewriting mechanism, comprising a hopper, reels, stencil strips winding about said reels and passing underneath said hopper, a passageway, having an offset at its upper end 115 communicating with said hopper, a cylinder, having projections upon the circumference thereof, extending into said passageway, levers with their free ends positioned adjacent to the circumference of said cylinder, said levers being tilted by the balls in contact with 120 the ends of the lever and depressed by a projection of said cylinder, the lower portion of the passageway having a lateral projection, the bottom of which is inclined and down which the ball is adapted to roll as it passes the cylinder, an elevating worm for raising a ball, a casing therefor, means within said casing for holding the balls in alinement as they are raised to a passageway leading from 125 said casing to the hopper, as set forth. 130
18. An automatic actuating apparatus for typewriting mechanism, comprising a hopper, reels, stencil strips winding about said reels and passing underneath said hopper, a passageway, having an offset at its upper end 135

communicating with said hopper, a cylinder, having projections upon the circumference thereof, extending into said passageway, levers with their free ends positioned adjacent to the circumference of said cylinder, said levers being tilted by the balls in contact with the ends of the lever and depressed by a projection of said cylinder, the lower portion of the passageway having a lateral projection, the bottom of which is inclined and down which the ball is adapted to roll as it passes the cylinder, an elevating worm for raising a ball, a casing therefor, a grooved strip mounted within said casing, designed to guide the balls as they are raised by said worm from the passageway leading from the upper end of the casing to said hopper, as set forth.

19. An automatic actuating apparatus for typewriting mechanism, comprising a hopper, a passageway, having an offset leading from said hopper, a stencil strip passing over said offset and beneath the hopper, reels upon which said strip is mounted, a driving shaft, a clutch mechanism for actuating one or the other of said reels, gear connections between said driving shaft and clutch mechanism, tilting levers, a rotatable drum fixed to said driving shaft, and angled levers actuated by said tilting levers, whereby said clutch mechanism may be actuated, as set forth.

20. An automatic actuating apparatus for typewriting mechanism, comprising a hopper, a passageway, having an offset leading from said hopper, a stencil strip passing over said offset and beneath the hopper, reels upon which said strip is mounted, a driving shaft, a gear wheel moving with each reel, a clutch for each reel, a rock shaft, crank arms fixed to said rock shaft and each having pivotal connection with a clutch, pivotally mounted angled levers adapted to actuate said rock shaft, a drum, having projections upon the circumference thereof, a series of levers designed, as they are tilted by a ball moved by said cylinder, to tilt one of said angled levers to actuate one or the other of said clutches, as set forth.

21. An automatic actuating apparatus for typewriting mechanism, comprising a hopper, a passageway, having an offset leading from said hopper, a stencil strip passing over said offset and beneath the hopper, reels upon which said strip is mounted, a driving shaft, a gear wheel moving with each reel, a clutch for each reel, a rock shaft, crank arms fixed to said shaft, and each having pivotal connection with a clutch, angled levers, an arm fixed to said rock shaft and actuated by said angled levers, a drum having a corrugated circumference, and levers actuated by balls which are moved by said drum, whereby said angled levers may be tilted, as set forth.

22. An automatic actuating apparatus

for typewriting mechanism, comprising a hopper, a perforated shaft mounted in the lower portion of said hopper, a crank arm secured to said perforated shaft, a passageway, having an offset leading from said hopper, a stencil strip passing over said offset and beneath the hopper, reels upon which said strip is mounted, a driving shaft, a gear wheel moving with said reel, a clutch for each reel, a rock shaft, crank arms fixed to said shaft and each having pivotal connection with a clutch, connections between said rock shaft and the crank upon said perforated shaft, angled levers, an arm fixed to said rock shaft and actuated by said angled levers, a drum having a corrugated circumference, and levers actuated by balls which are moved by said drum, whereby said angled levers may be tilted, as set forth.

23. An automatic actuating apparatus for typewriting mechanism, comprising two hoppers, two sets of reels, stencil strips, one carried by said set of reels, balls in said hoppers, passageways, having offsets communicating with said hoppers, a driving shaft, a cylinder rotating therewith, tilting levers, a bevel gear loosely journaled upon said driving shaft, a clutch splined to the latter, gear connections between said loosely journaled bevel gear and a bevel gear mounted upon one of said reels, whereby one of said strips may be moved, a pivotal lever positioned underneath one of said tilting levers and having an arm connected to said splined clutch, and means actuated by one of said tilting levers for causing the clutch mechanism to move a reel carrying the other of said stencil strips, as set forth.

24. An automatic actuating apparatus for typewriting mechanism, comprising a hopper, a stencil strip, reels upon which said strip is mounted, a passageway, with an offset leading from said hopper, a corrugated cylinder, a shaft to which the same is fixed, a tilting lever operated by a ball which is moved by said cylinder, a bevel gear loosely journaled upon said shaft, a clutch splined to the latter, gear connections between said bevel gear and one of said reels, an angled lever having a shank portion, which is adapted to be depressed by one of said tilting levers, a projection of said angled lever having a double beveled end, a stationary resilient arm, having a beveled projection thereon adapted to contact with the end of said projection of the arm of the lever, as set forth.

25. An automatic actuating apparatus for typewriting mechanism, comprising a hopper, a stencil strip, reels upon which said strip is mounted, a passageway, with an offset leading from said hopper, a corrugated cylinder, a shaft to which the same is fixed, a tilting lever operated by a ball which is moved by said cylinder, a bevel gear loosely journaled upon said shaft, a clutch splined

to the latter, gear connections between said bevel gear and one of said reels, an angled lever having a shank portion, which is adapted to be depressed by one of said tilting levers, a projection of said angled lever having a double beveled end, a stationary resilient arm, having a beveled projection thereon adapted to contact with the end of said projection of the arm of the lever, a second angled lever which is spring-pressed, having a lug designed, as a tilting lever is depressed, to actuate said clutch throwing lever, as set forth.

26. An automatic actuating apparatus for typewriting mechanism, comprising a hopper, a passageway leading therefrom, a stencil strip, reels upon which said strip is mounted, balls mounted in said hopper, adapted to be fed by said stencil strip into said passageway, an operating shaft, a corrugated drum fixed to said shaft, tilting spring-actuated levers, a rock shaft, gear wheels loosely journaled upon the spindles of said reels, a clutch wheel splined to each spindle of the reel, gear connections between the operating shaft and said gear wheels on the reel spindles, a rock shaft, connections between said rock shaft and said clutches, tilting angled levers, a crank arm fixed to said rock shaft and adapted to be tilted by said angled levers, a projection of said crank arm which is fixed to said shaft, having a double tapering end, a stationary resilient arm having a projection upon one edge thereof, which is notched and adapted to receive the double tapering end of said projection, whereby as said shaft is rocked a certain distance by one of said angled levers, said clutches may be held out of gear, as set forth.

40 27. In combination with a hopper with balls therein, a passageway leading therefrom, means carried by the latter for feeding singly a ball into said passageway, a driving shaft, a rotatable drum fixed to said shaft, having projections upon the circumference thereof, a tilting lever, a punch carried by said lever, winding reels, a strip adapted to pass beneath said punch and to wind upon one of said reels, and means for imparting an intermittent movement to said winding reels, as set forth.

28. In combination with a hopper with balls therein, a passageway leading therefrom, means carried by the latter for feeding singly a ball into said passageway, a driving shaft, a rotatable drum fixed to said shaft, having projections upon the circumference thereof, a tilting lever, a punch carried by said lever, winding reels, the lower portion of

said passageway having a transverse slot, 60 and a strip passing through said slot and winding upon one of said reels, and means for imparting an intermittent movement to the reel, as set forth.

29. In combination with a hopper with 65 balls therein, a passageway leading therefrom, means carried by the latter for feeding singly a ball into said passageway, a driving shaft, a rotatable drum fixed to said shaft, having projections upon the circumference 70 thereof, a tilting lever, a punch carried by said lever, a winding reel, the lower portion of said passageway having a transverse slot, a strip passing through said slot and winding about said reel, a ratchet wheel rotating with 75 said reel, a crank loosely journaled upon the spindle of said reel, a dog carried by said crank arm, engaging the teeth on said ratchet wheel, and lever and gear connections intermediate said crank arm and said driving 80 shaft, as set forth.

30. In combination with a hopper, with 90 balls therein, a passageway leading from said hopper, a spring-pressed plunger mounted horizontally within said hopper, and adapted to feed a ball singly into said passageway, a driving shaft, a drum fixed thereto, having a corrugated circumference, a series of spring-actuated tilting levers, a punch pivotally connected to a lever, a guide in which said punch 95 works, a winding reel, a strip passing through a slot in the lower portion of the slot of said passageway and underneath said punch, and means for imparting an intermittent movement to said reel, as set forth. 95

31. In combination with a hopper with 100 balls therein, a passageway leading from said hopper, a spring-pressed plunger mounted horizontally within said hopper, and adapted to feed a ball singly into said passageway, a driving shaft, a drum fixed thereto, having a corrugated circumference, a series of spring-actuated tilting levers, a punch pivotally connected to the lever, a guide in which said punch works, a winding reel, a strip passing 105 through a slot in the lower portion of the slot of said passageway and underneath said punch, means for imparting an intermittent movement to said reel, and a series of key levers pivotally mounted upon the hopper and having connection with said plungers, as set forth.

In testimony whereof I hereunto affix my signature in the presence of two witnesses.
